Inventor:

William Ambler,

By J. Adelvao.

Attorney.

UNITED STATES PATENT OFFICE.

WILLIAM AMBLER, OF BRADFORD, ENGLAND.

WATER-TUBE FOR STEAM-GENERATORS.

No. 799,961.

Specification of Letters Patent.

Patented Sept. 19, 1905.

Application filed May 8, 1904. Serial No. 206,204.

To all whom it may concern:

Be it known that I, WILLIAM AMBLER, a subject of the King of Great Britain and Ireland, and a resident of Bradford, England, have invented certain new and useful Improvements in Water-Tubes for Steam-Generators, (for which I have filed an application for British Patent No. 15,194, dated July 9, 1903;) and I do hereby declare the following to be a full, 10 clear, and exact description of the same.

This invention relates to steam-generators and water-tubes therefor of that class wherein the tubes project from the water-chamber into the fire-chamber of the generator, and 15 has for its main object to facilitate the liberation of steam and to improve the water circulation within such tubes and to obtain a consequent more economical utilization of fuel.

To this end the invention is characterized 20 by the application to the water-tube of a division-plate so adapted as to partition it longitudinally into under and upper compartments, which continue the one into the other at the closed end of the water-tube, where a 25 sufficient space is left between the water-tube and division-plate for a free flow of the water, and as to cause the inlet to the under compartment from the water-chamber of the generator to be at a level lower than that of the 30 outlet from the upper compartment to said water-chamber, so as to cause the under compartment to serve for the downflow from said water-chamber and such downflow to be subjected to the greatest heat and the upper 35 compartment to serve for the return or up current back to said water-chamber, and as to connect such compartments at a plurality of places along the division-plate by inclined channels adapted to facilitate the liberation 40 of steam generated in the downflow-compartment and its escape to the upflow-compartment, so as to maintain the water-body circulating through the compartment subjected to the greatest heat at practically the density of 45 its inlet, and consequently at its highest heat conductivity, and at the same time to decrease the density of the water-body circulating through the upflow-compartment by the displacement effected by the steam particles escaping thereinto, and so to improve the circulation.

On the accompanying drawings, Figure 1 represents a generator water-chamber fitted

with inclined water-tubes adapted in accordance with the invention. Fig. 2 represents 55 an application of horizontal water-tubes so adapted. Fig. 3 represents an inner end elevation and a section of the water-tube represented in Fig. 1. Fig. 4 represents like views of the water-tube represented in Fig. 2, and 60 Fig. 5 represents different formations of the division-plate.

a represents the generator water-chamber, *a'* a depending extension therefrom having a partition *a'*, and *b* the water-tube which projects from said chamber or extension into the fire-chamber. *d* represents said division-plate, which may be flat or arched and is arranged diametrically of the water-tube, so as to partition the tube into under and upper 70 compartments *b'* *b*², which continue the one into the other at the closed end *b*³. The inlet *e* from the chamber *a* or its extension to the compartment *b'* is located at a level lower than that of the outlet *f* from the compartment *b*² 75 to such chamber or extension, so as to cause the compartment *b'* to serve for the down-current and such current to be subjected to the most intense heat and the compartment *b*² to serve for the upcurrent. 80

Throughout or for the greater part of its length the division-plate is adapted to connect the compartments *b'* *b*² at a plurality of places by inclined channels *d'*, having upper or under projecting parts or ducts *d*² adapted to 85 intercept or lead any steam particles generated within the compartment *b'* and conduct them to the compartment *b*², whence they escape with the return-current, so as to free the downflow-water from such particles and leave 90 the same in a denser condition of correspondingly higher heat conductivity, while lessening the density of the upflow-water.

What I claim is—

1. In a steam-generator, a water and steam chamber, a water-tube projecting downward from the lower portion of the water and steam chamber closed at the outer end, a division-plate extending downward from the mouth of the tube nearly to the closed end thereof dividing the water-tube into two chambers or passages communicating at the outer end, such division-plate having orifices at intervals through the same forming communications between the two chambers, and also flanges 100 projecting into the lower chamber or passage 105

of the water-tube from the upper edges of the orifices in the division-plate inclined in the direction of the flow, substantially as shown and described.

5. 2. In a steam-generator, a water and steam chamber, a downwardly-inclined water-tube projecting downward from the lower portion of the water and steam chamber closed at the outer end, a division-plate extending downward from the mouth of the tube nearly to the closed end thereof dividing the water-tube into two chambers or passages communicating at the outer end, such division-plate having orifices at intervals through the same forming 15 communications between the two chambers, and also flanges projecting into the lower chamber or passage of the water-tube from the upper edges of the orifices in the division-plate inclined in the direction of the flow, substantially as shown and described.

3. In a steam-generator, a water and steam chamber, a water-tube projecting downward from the lower portion of the water and steam chamber closed at the outer end, a division- 25 plate extending downward from the mouth of the tube nearly to the closed end thereof dividing the water-tube into two chambers or passages communicating at the outer end, such division-plate having orifices at intervals 30 through the same forming communications between the two chambers, and also flanges projecting into the lower chamber or passage of the water-tube from the upper edges of the orifices in the division-plate inclined in the 35 direction of the flow, such flanges being formed integral with the division-plate, substantially as shown and described.

4. In a steam-generator, a water and steam chamber, a downwardly-inclined water-tube 40 projecting downward from the lower portion of the water and steam chamber closed at the outer end, a division-plate extending downward from the mouth of the tube nearly to the closed end thereof dividing the water-tube 45 into two chambers or passages communicating at the outer end, such division-plate having orifices at intervals through the same forming communications between the two chambers, and also flanges projecting into the lower 50 chamber or passage of the water-tube from the upper edges of the orifices in the division-plate inclined in the direction of the flow, such flanges being formed integral with the division-plate, substantially as shown and described.

5. In a steam-generator, a water and steam chamber, a water-tube projecting downward from the lower portion of the water and steam chamber closed at the outer end, a division- 60 plate extending downward from the mouth of the tube nearly to the closed end thereof dividing the water-tube into two chambers or

passages communicating at the outer end, such division-plate having orifices at intervals through the same forming communications between the two chambers, the two chambers or 65 passages of the water-tube communicating with the water and steam chamber at different heights, and also flanges projecting into the lower chamber or passage of the water-tube 70 from the upper edges of the orifices in the division-plate inclined in the direction of the flow, substantially as shown and described.

6. In a steam-generator, a water and steam chamber, a downwardly-inclined water-tube 75 projecting downward from the lower portion of the water and steam chamber closed at the outer end, a division-plate extending downward from the mouth of the tube nearly to the closed end thereof dividing the water-tube 80 into two chambers or passages communicating at the outer end, such division-plate having orifices at intervals through the same forming communications between the two chambers, the two chambers or 85 passages of the water-tube communicating with the water and steam chamber at different heights, and also flanges projecting into the lower chamber or passage of the water-tube from the upper edges of the orifices in the division-plate inclined in the 90 direction of the flow, substantially as described.

7. In a steam-generator, a water and steam chamber, a water-tube projecting downward from the lower portion of the water and steam chamber closed at the outer end, a division- 95 plate extending downward from the mouth of the tube nearly to the closed end thereof dividing the water-tube into two chambers or passages communicating at the outer end, such division-plate having orifices at intervals 100 through the same forming communications between the two chambers, the two chambers or passages of the water-tube communicating with the water and steam chamber at different heights, and also flanges projecting into the 105 lower chamber or passage of the water-tube from the upper edges of the orifices in the division-plate inclined in the direction of the flow, such flanges being formed integral with the division-plate, substantially as shown and 110 described.

8. In a steam-generator, a water and steam chamber, a downwardly-inclined water-tube projecting downward from the lower portion of the water and steam chamber closed at the outer end, a division-plate extending downward from the mouth of the tube nearly to the closed end thereof dividing the water-tube 115 into two chambers or passages communicating at the outer end, such division-plate having orifices at intervals through the same forming communications between the two chambers, the two chambers or 120 passages of the water-tube communicating with the water and steam

chamber at different heights, and also flanges projecting into the lower chamber or passage of the water-tube from the upper edges of the orifices in the division-plate inclined in the direction of the flow, such flanges being formed

5 integral with the division-plate, substantially as shown and described.

In testimony whereof I have signed this specification in the presence of two subscribing witnesses.

WILLIAM AMBLER.
